UNITED STATES PATENT OFFICE.

ALFRED G. BROWN, OF WINONA, MINNESOTA, ASSIGNOR TO UNION FIBRE COMPANY,
OF WINONA, MINNESOTA, A CORPORATION OF MINNESOTA.

CAR INSULATION.

1,156,206.

Specification of Letters Patent.

Patented Oct. 12, 1915.

Application filed January 10, 1913. Serial No. 741,223.

To all whom it may concern:

Be it known that I, ALFRED G. BROWN, a citizen of the United States, residing at Winona, in the county of Winona and State of Minnesota, have invented certain new and useful Improvements in Car Insulation, of which the following is a specification.

My invention relates to improvements in insulation constructions, its object being particularly to provide an improved insulated construction of car floor and connected side walls which will prevent water from getting to the interior insulation to deteriorate the same, and which will also prevent the interior insulation from being affected by the driving of ordinary nails or spikes into the floor of the car.

To this end the invention consists in the features of construction, combination, and arrangement of parts hereinafter described and claimed.

In the accompanying drawings forming part of this specification, Figure 1 is a perspective view of a car floor and connected side wall broken away and containing my improved features of invention; Fig. 2 is a transverse vertical section through a car body containing my features of invention; and Fig. 3 is a similar view through a portion of the floor and connected side wall enlarged.

Referring to the drawings, A represents the outer side wall sheathing of the car, and B the spaced floor timbers. In building up the floor construction strips 2 will first be secured along the inner faces of the floor timbers and upon this is arranged the flooring 3, preferably of ordinary tongued and grooved material. The flooring 3 will then be covered by a layer of suitable water-proof material 4, as water-proof paper. Upon the paper 4 are placed layers of insulating material 5. Where some kinds of insulation, as the well known Linofelt insulation is used, furring strips 6 may be placed between the layers. With certain other well known kinds of insulation, such furring strips will not be necessary. The insulation being pressed into place between the timbers 50 is covered by a layer of water-proof material 7, such as water-proof paper, the side edges of the paper being turned up along the inner faces of the sills to the top thereof. A plurality of pieces of board 8 are then placed upon the water-proof paper 7, and

interspaced from the timbers and from each other preferably about a quarter of an inch. Said pieces of board 8 constitute a protecting filler for the insulation 5, the wood fillers serving as nailing strips to prevent the insulation from being pierced by spikes driven through the car floor. A suitable water-proof material 9, such as antiaqua is then poured in liquid state around and on top the pieces 8, the antiaqua preferably extending upwardly flush to the tops of the sills. It will be understood that this water-proof material will be of a kind that will harden but not become brittle upon becoming hard. A layer of rubberoid or equivalent water-proof paper 10 will then be laid upon the tops of the sills and the filling 9, covering the entire bottom of the car, said water-proof paper, as shown, extending outwardly under the inner layers of the side wall insulation and upwardly along the inner face of the outer layer of side wall insulation. Upon the water-proof paper 10 will be laid the flooring 11 extending, as shown, outwardly underneath the inner layers of side wall insulation.

The side wall of the car is made up, as shown, of the outer sheathing A inside of which is arranged an outer layer of insulating material 12 between the frame 13 and outer sheathing. Inside the frame is shown two inner layers 14 and 15 of insulation interposed between the frame 13 and inner sheathing 16 of the side wall. The bottom edges of the inner layers 14 and 15 of insulation are shown enveloped by water-proof paper 17 laid on top of the floor. In building up the side wall of the car a water-proof material 9, similar to that employed in the flooring, is poured behind the first layer of inner sheathing, whereby to prevent water getting from the floor to the side wall insulation.

It will be apparent that the layers of insulation 5 are thus protected on the underside from moisture by the false flooring and under layer of water-proof paper and upon the other side by the two layers of water-proof paper, as well as by the pieces of board 8 and the enveloping water-proof compound. It will thus be impossible for any water that may collect upon the inner car floor, as in washing the car, handling ice therein, etc., to penetrate through to the layers of insulation. Another great advan-

tage is that the ordinary spikes used in
cleating the center of the car to support
freight cannot penetrate through the pieces
of board 8 and surrounding water-proof ma-
5 terial to the layers of insulation. In the
ordinary insulated car floor constructions
the spikes employed make holes through
which water passes to the layers of insula-
tion, causing deterioration. This has been
10 a problem in insulated car floor construc-
tions that has not been heretofore success-
fully solved. I also, by means of the par-
ticular character of water-proof connection
shown between the floor and bottom of the
15 side wall insulation, prevent the water from
getting to the bottom of the side wall insula-
tion to cause its deterioration.

By means of the features of invention
shown, I thus secure a construction of in-
20 sulated bottom and side walls which is abso-
lutely protected from water which ordi-
narily collects on the inner floor of the car,
and which in the ordinary constructions
causes deterioration of the layers of insula-
25 tion.

I claim as my invention:

1. A floor construction for cars, comprising in combination with floor timbers, a built-up insulating structure contained
30 wholly between said timbers, said insulating structure consisting of a plurality of layers of insulation supported by said timbers, filler blocks inserted in spaced relation across the openings between said timbers
35 and above said insulation, and a plastic material poured around said filler blocks and filling the remainder of the space to the upper level of the floor timbers, and the
flooring laid over said timbers.
- 40 2. A floor construction for cars, comprising in combination with floor timbers, a false flooring provided between said timbers, and an insulating structure built-up upon said false flooring said insulating structure
45 consisting of a plurality of layers of insulation laid upon said false flooring, filler blocks laid upon said insulation, and water
proofing material surrounding said blocks
50 and filling space between said timbers to the
upper level thereof, and a flooring laid upon
said timbers.

- 55 3. A floor construction for cars, comprising in combination with floor timbers, a false flooring supported between said timbers, and an insulating structure supported

by said false flooring, said insulating struc-
ture consisting of layers of insulation laid
upon said false flooring, filler blocks laid
upon said insulation and extending across
the space between said timbers, and a plastic 60
water-proofing material separating said
blocks from one another and from said tim-
bers, said plastic material also filling the re-
mainder of the space between said timbers
to the upper level of the latter. 65

4. A floor construction for cars, comprising in combination with floor timbers, a false flooring mounted between said timbers, and a built-up insulation laid upon said
false flooring, said insulation consisting of 70
a plurality of layers of insulating material,
filler blocks laid upon said insulating mate-
rial and spaced from one another and from
said timbers, and a plastic water-proofing
material poured around said filler blocks 75
and filling the remainder of the space be-
tween said timbers to the upper level there-
of, said plastic material and filler blocks
protecting said insulation from damage by
articles driven into said insulation. 80

5. A car floor and wall construction, com-
prising in combination, floor timbers and car
framing, a false flooring supported between
said timbers and providing channel-like
spaces therebetween, a plurality of layers of
85 insulation laid upon said false flooring,
layers of insulation also secured to said car
framing, filler blocks placed in said channel-
like spaces above said insulation in water-
proofed relation thereto, a plastic water- 90
proofing material spacing said blocks from
one another and from said timbers, said
plastic material also filling the remainder of
said spaces to the upper level of said tim-
bers, a flooring laid upon said timbers, a 95
water proofing material interposed between
said timbers and said floor and extending
below the inner layers of insulation on said
car frame, and vertically overlying the lower
portion of the outer layer of insulation on
100 the car frame, and a layer of water proofing
plastic between said floor and the lower in-
ner edge of the insulation of the car wall.

In testimony whereof I affix my signature
in presence of two witnesses.

ALFRED G. BROWN.
